UNITED STATES PATENT OFFICE.

CLAYTON M. HAMILTON, OF LAKE VILLAGE, NEW HAMPSHIRE.

DESIGN FOR A LOOM-PICKER.

SPECIFICATION forming part of Design No. 17,427, dated July 5, 1887.

Application filed January 25, 1887. Serial No. 225,500. Term of patent 7 years.

To all whom it may concern:

Be it known that I, CLAYTON M. HAMILTON, a citizen of the United States, residing in Lake Village, in the county of Belknap and State of New Hampshire, have invented and produced 5 a new and original Design for a Loom-Picker; and I do hereby declare that the following is a full and exact description of the same, reference being had to the accompanying drawings, making part of this specification.

Figure 1 is a side view of my newly-designed loom-picker. Fig. 2 is a side view of the same, taken in a position at right angles to that in Fig. 1; Fig. 3, a central longitudinal 15 section of the same in a plane indicated by the line xx , Fig. 1; Fig. 4, an end view of the same.

Like letters designate corresponding parts in all of the figures.

The leading feature of my design consists in 20 the cylindrical form of the body A of the picker, both inside and outside. This body

has an inwardly-projecting lip, a, on its inner periphery at its outer end. The outer edge of the body is generally rounded over from the outside inward to the lip, as shown in Fig. 25 3. The inner end of the body is at right angles to the sides, except where it is joined to the straps B B.

I claim—

In a design for a loom-picker, the body A, 30 having a cylindrical form inside and outside, an inwardly-projecting lip at the outer end, the end rounded over from the outside to the lip, and having a right-angled inner end, substantially as shown and described. 35

In witness whereof I have hereunto signed my name in the presence of two subscribing witnesses.

CLAYTON M. HAMILTON.

Witnesses:

J. M. HUBBARD,
E. A. PHILBRICK.
